UNITED STATES PATENT OFFICE.

SIDNEY W. MILLER, OF CHICAGO, ILLINOIS.

SIPHON.

SPECIFICATION forming part of Letters Patent No. 749,445, dated January 12, 1904.

Application filed December 26, 1902. Serial No. 136,681. (No model.)

To all whom it may concern:

Be it known that I, SIDNEY W. MILLER, of Chicago, in the county of Cook and State of Illinois, have invented certain new and useful Improvements in Siphons; and I do hereby declare that the following is a full, clear, and exact description thereof, reference being had to the accompanying drawings, and to the letters of reference marked thereon, which form a part of this specification.

This invention relates to an apparatus designed for controlling the flow of liquid from a main tank or receptacle which is adapted to be alternately emptied into a plurality of tanks or receptacles and so arranged that said plurality of receptacles may be filled or charged from the main tank in a predetermined rotative order.

An apparatus embodying my invention is generally like that shown in the prior application for United States Letters Patent of Moses James Adams, Serial No. 129,265, filed October 29, 1902, wherein a number of siphons are located in a single tank and designed to be brought alternately into operation to empty said tank.

The apparatus may be used wherever it is desired to distribute liquid from a central or dosing tank to a number of outlying tanks or receptacles and is especially applicable for use in connection with a system employed for the septic treatment of sewage to purify the same, the apparatus being located when used for this purpose between the septic-tank and the contact or filter beds of a sewage-purifying system, so as to receive the sewage from the septic-tank and properly distribute the same over the contact or filter beds.

One of the objects of the present invention is to simplify the connections between several siphons located in or draining a single receptacle, whereby as many siphons as desired may be practically operated in a single tank or receptacle, and a further object of the invention is to so connect the several siphons as to enable one or more of the siphons to be cut out of the operative series and to change the order of rotation of the siphons.

The invention consists of the matters hereinafter set forth, and more particularly pointed out in the appended claims.

In the drawings, Figure 1 is a plan view of an apparatus embodying my invention. Fig. 2 is a transverse vertical section thereof taken on line 2 2 of Fig. 1. Fig. 3 is a horizontal section taken on line 3 3 of Fig. 2. Fig. 4 is a transverse vertical section taken on the oblique line 4 4 of Fig. 1. Figs. 5, 6, and 7 are diagrammatic views illustrating three stages of the operation of the siphons.

As shown in the drawings, A designates a tank which may be termed a main "distributing" or "dosing" tank and is adapted for connection with a source supplying liquid—such, for instance, as a septic-tank—through the medium of a pipe A'. Said tank is usually made of masonry or concrete structure and when used in connection with a sewage-purifying system is usually made of sufficient capacity to contain a charge of sewage sufficient to fill either of the contact or filter beds in connection with which it is used. The contents of said tank is designed to be emptied into a plurality of receptacles (not shown) through the medium of a plurality of siphons B B' B² B³, which are located in said tank, near one side thereof, as herein shown. The short or intake limb b of each siphon, as shown, consists of a downwardly-opening bell which is supported over the upper end of the longer limb b'. Said longer limb of each siphon communicates with a deep seal-trap b², the shorter or outlet limb of which empties into a pipe or conduit C, which leads to one of the contact or filter beds or other suitable place for the disposal of liquid discharged through the siphon. When the siphons are installed and prior to the commencement of their operation, the traps thereof may all be filled with liquid, and when the tank has been almost filled one of the siphons may be set into operation before the others through some mechanical contrivance or one of the traps of said siphons may be only partially filled, so that the siphon associated therewith will be the first to operate. During the operation of the initially-operable siphon to empty the tank the trap of said siphon is automatically filled by the liquid, which passes thereinto from the tank, and the several siphons are so connected, as in the prior Adams construction before mentioned, that the traps of all

of the siphons excepting the one next to be brought into operation (and usually the siphon next in advance of the siphon just operated with respect to the direction of rotative order of operation of the siphons) are refilled or reprimed, so that when the tank is again filled a single one of the siphons has a partially-filled trap, and therefore a seal which will be overcome before the seals of the other 10 siphons, whereby the siphon so having the partially-filled trap will be brought next into operation to empty the tank, the other siphons in the tank remaining at this time idle or inoperative. I have herein termed the 15 seal of the partially-filled trap a "weakened" seal, for the reason that it is the first seal to be forced when the tank is again filled, though of course it is understood that the depth of the liquid column in the outlet limb of the 20 trap at the time the siphon is forced remains unchanged. The means for maintaining said predetermined rotative order of operation of the siphons herein shown are constructed as follows: Associated with said siphons and located in the tank A are a number of chambers or wells D to D³, one for each siphon. The siphons are herein shown as arranged in a straight row, and the chambers or wells are similarly disposed in rear of the siphons. 25 The siphons may, if desired, be arranged in a circular series with the chambers or wells D to D³ located either inside or outside of said circular series. Said chambers D to D³ extend below the bottom or floor of the tank A 30 to provide sealing-chambers d, as shown in Figs. 2 and 4.

E designate a plurality of siphons associated one with each chamber or well. The intake-limb of each siphon is located in one of 40 the chambers or wells D to D³, and the outlet-limb thereof is connected with the adjacent siphon through the medium of a connecting-pipe e, the pipe e entering the longer limb of the siphon or its trap. The lower ends of the 45 receiving-limbs of the siphons E extend into the sealing extension of the chambers D to D³. Each of the chambers or wells D to D³ is provided with another siphon, F, which is preferably located wholly within said chamber, with 50 its lower end extending into the sealing extension of said chamber. The outlet-limb of each of said siphons F discharges through the medium of a connecting-pipe f into one of the siphons B to B³ or the trap thereof which is located in advance of the siphon which communicates through one of the siphons E with the associated chamber of said siphon F. It will be seen, therefore, that each of the chambers D to D³ is connected directly with its associated 55 siphon through one of the siphons E and is connected with another siphon of the series B to B³ located in advance of the first-mentioned siphon with respect to the sequence of operation of the siphons B to B³ through one 60 of the siphons F. Both of the siphons E F of

said chambers are adapted at the proper time in the operation of the apparatus to drain their associated wells or chambers D D³. It may be here stated that it is not essential that the siphons F be located wholly within the 70 chambers D to D³ or the receiving-limb of the siphons E extend into said chambers, through the tops thereof, so long as they are arranged to empty said chambers in the manner hereinafter to be described.

The operation of the apparatus is as follows: It may be assumed that before filling the tank A all of the traps of the siphons B to B³ but one—the trap of siphon B, for instance—is filled, the latter trap being but partially filled, as shown in Fig. 5, said Fig. 5 illustrating the level of the liquid in the tank and the several traps before the tank A is filled. After said traps have been filled or primed in the manner shown the tank A is 80 filled through the pipe A', and as said tank is being filled the liquid in the longer or intake limbs of the several traps is depressed. As the depression of the liquid takes place in the intake-limbs of the traps which are filled, it 85 escapes in corresponding quantities from the upper end of the outlet-limbs of said traps. The depression of the liquid in the longer leg of the partially-filled trap and its rise in the intake-limb of the siphon having such partially-filled trap, however, takes place more slowly until after the liquid begins to flow from said trap, for the reason that up to this time the difference between the liquid-levels 90 in the two limbs of the trap becomes greater 95 relatively to the corresponding levels in the filled traps, and the pressure required to force the liquid to the shorter or outlet leg of the trap which was partially filled is gradually increased. When a certain depth of liquid in 100 the tank A is reached, the liquid in the longer limb of the partially-filled trap (the trap of siphon B in the present instance) is depressed, as shown in Fig. 6, until the seal is forced and the siphon B started into operation to empty 105 the tank A. When such operation of the siphon B takes place, the liquid of the tank A will be discharged through said siphon; but the other siphons B' B² B³ will remain idle or inactive, as the pressure exerted by the liquid-head in the tank is insufficient to force the seals in the traps of said siphons, as is clear 110 from an inspection of said Fig. 6. The reason why one siphon of the series is thus brought 115 into action and the others remain idle may be 120 understood from the following: Owing to the fact that the liquid in the unfilled trap stands a considerable distance below the overflow end of the outlet side of the trap the depression of the liquid in the inlet side of said trap 125 raises the level of the liquid in the outlet side of the trap a corresponding distance, so that a unit depression in the inlet side or limb of the trap is represented by a difference of two 130 units in the liquid-level between said limbs of

the trap and the difference between the liquid-levels in the limbs of said trap increases at each instant of depression in the inlet side of the trap in the same ratio until the liquid overflows from the upper end of the outlet-limb of the trap. In the case of the traps which were entirely filled a unit depression of the liquid in the intake sides of the traps represents a unit difference in the liquid-levels 5 between the inlet and outlet limbs of the traps. It follows, therefore, that the difference between the levels of liquid in the limbs of the partially-filled trap becomes gradually greater during the period mentioned relatively to the corresponding levels in the limbs 10 of the traps which were entirely filled, and the resistance to the rise of the liquid in the intake-limb of said siphon B is correspondingly greater, and the rise will take place more 15 slowly under the same rise of liquid in the tank than in the intake-limbs of the traps which were wholly filled. As a consequence of this condition it follows, if no account be 20 taken of the effect of friction and compression 25 of the column of air in the siphon and trap, that a unit difference between the liquid-levels in the limbs of the partially-filled trap is represented by a rise of liquid in the intake-limb of the associated siphon of half a unit, while 30 a corresponding difference in the levels of the traps which were entirely filled is represented by a rise of a unit in the intake-limbs of the siphons associated with said traps. It will be 35 seen, therefore, that the rise of liquid in the intake-limb of the siphon having the partially-filled trap is slower when working under the same level in the tank A than in the intake-limbs of the siphon having their traps entirely filled, so that a height of liquid in the tank 40 measured from the sealing-levels of the siphons required to produce a head to force the siphon having its trap partially filled is insufficient to produce a head required to force the siphons having their traps entirely filled. 45 If no account be taken of the effect of friction and the depression of the columns of air in the siphons and traps, the liquid will rise in the intake-limbs of the siphons to an extent equal to the depression of the liquid in the intake 50 sides of the traps, as before stated. Owing to such compression, however, and the retarding effect of friction the rise of liquid in the intake-limbs of the siphons is slightly greater than the depression of the liquid in the intake 55 sides of the traps. In designing deep-trap siphons of this character, however, it is the practice of engineers to so proportion the parts of the siphons as to provide a margin of safety which will insure that the liquid in the intake-limb of the siphon will not rise so high before its seal is overcome or forced by the liquid-head in the tank as to overflow the receiving end of the longer limb of the siphon. Such 60 margin of safety is computed with respect to the dimensions of the intake-limb of the siphon

relatively to the length and diameter of the outlet-limb of the siphon and of the trap. Having provided such margin of safety in a plurality of siphons operating in the manner herein set forth to empty a tank, (which margin will be the same for all the siphons,) it is found that the difference between the compression of the air-columns in the siphons having the filled and unfilled traps and the differences between the effects of friction are so 70 small that they need not be taken into consideration when installing the siphons to operate in the manner hereinbefore described—for instance, an eight-inch-deep trap siphon of uniform diameter from the intake-limb of the siphon to the outlet-limb of the trap and having a trap of 2.27 feet in depth the difference in compression of the columns of air (measured in linear feet) between a siphon having its trap half filled and one having its trap 75 entirely filled is approximately .07 of a foot, and the difference between the effect of friction in two such siphons is inconsiderable. In practice, therefore, it may be assumed with substantial accuracy that after the intake-limbs 80 of the siphon arranged and operating as herein shown are sealed (which occurs in this instance when the lower ends of the auxiliary vent-pipes shown are submerged) the liquid rises in the intake-limbs of the siphons in a 85 quantity substantially equal to that displaced in the intake sides or limbs of the deep-seal traps, the difference between the rise of liquid in the intake-limbs of the siphons and the depression of the liquid in the intake sides of 90 the trap due to the compression of air and effects of friction being so small relatively to the difference of levels in the tank necessary to bring the siphons into operation that it need not be taken into account, as above stated. It 95 will be observed, therefore, that the height to which the liquid rises in the intake-limbs 100 of the siphons is dependent upon the quantity of liquid originally contained in the intake sides of the traps, the rise in the intake-limbs 105 of the siphons corresponding in quantity to the quantity of liquid displaced from the intake sides of the traps plus the height of the liquid column represented by the compression of the columns of air in such siphons 110 and traps and by the effect due to friction. As the head of liquid in the tank necessary to force the traps of several siphons located therein is always the same under similar conditions of proportions and levels, (and it is 115 assumed that the siphons are set or proportioned to operate under similar conditions of head,) the liquid is required to rise to a greater height in the tank (measured from the sealing-levels of the intake-limbs of the 120 siphons) to force the traps originally filled than to force the trap only partially filled, the liquid in the intake-limbs of the siphons having wholly-filled traps rising to a greater 125 height than in the siphon having a partially- 130

filled trap. This is because of the fact that, as before stated, the liquid rises more slowly in the intake-limb of the siphon having the partially-filled trap than in the siphons having the wholly-filled traps and also because there is less liquid to be displaced in the intake side of the partially-filled trap than in the intake sides of the wholly-filled traps. It will be seen, therefore, that a greater depth 5 of water in the tank is required to set into operation the siphons having wholly-filled traps than to set into operation the siphon having the partially-filled trap. When, therefore, a plurality of siphons are located in the same 10 tank and are so proportioned or set as to operate under the same conditions of liquid-head and the trap of one of the siphons is partially filled, while the traps of the other siphons are entirely filled, the siphon having 15 20 the partially-filled trap is first brought into operation, for the reason that (as the liquid does not rise so high in the intake-limb thereof as in the other siphons with the same depth of liquid in the tank) when the depth of liquid in the tank is sufficient to force the trap which was partially filled it is not sufficient to force the traps which were wholly filled. This will be made clear upon an inspection of 25 Fig. 6 of the drawings, which illustrates the 30 tank filled to the depth required to force the trap of siphon B, which originally had a partially-filled trap, and from such inspection it will be observed that the difference between the level of the liquid in the intake-limbs of 35 siphons B' B² B³ and the level of the liquid in the tank is less than the depth of the seals of their traps and not sufficient to produce a head to force their traps. It is evident that when siphonic action is started in siphon B 40 45 the tank will be emptied through said siphon B to the sealing-level of the mouth of the intake-limb of said siphon B and that the other siphons will remain idle. This is due to the fact that the air locked in the siphons B' B² B³ is not released until the liquid-level in the 50 tank is below the sealing-level of said siphons B' B² B³, and when this occurs the tank-level is below the intake ends of the longer limbs of said siphons B' B² B³, so that liquid from 55 60 the tank will not flow therethrough. By reason of the connection of said siphon B with its associated chamber or well D through the medium of one of the siphons E and its connecting-pipe e said siphon E acts at the time of the operation of said siphon B to empty the liquid from the chamber or well D through said siphon B. The other chambers or wells D' D² D³ are not, however, emptied through the siphons E into and through their 65 70 associated siphons B' B² B³, for the reason that the pressure existing in said siphons B' B² B³ due to the liquid-head in the tank A is such as to prevent operation of said last-mentioned siphons E, said pressure holding the siphons E, associated with the idle siphon, out of op-

eration until the level of the liquid drops below the operating-level of the siphons E. It will be understood that the operating-siphon (the siphon B in the instance assumed) will fill its own trap during the emptying operation 70 in the usual manner, so that when the emptying operation ceases the trap of said siphon B is filled, as shown in Fig. 7. The traps of the other siphons B' B² B³ are not filled in this manner, because there is no flow of liquid 75 therethrough during the emptying of the tank. Consequently if said siphons B' B² B³ were not provided with filling means the amount of liquid remaining in the traps thereof after the tank is emptied is only a little more than that 80 contained in the shorter limbs of said traps just before the tank is emptied, the liquid from the shorter limbs of the traps settling back upon the diminishment of pressure in the siphons partially into the longer limbs thereof 85 until the levels are equal in both limbs of each trap. 90 By reason of the connection of the several siphons B to B³, inclusive, with the several wells or chambers D to D³, inclusive, through the siphons F and connecting-pipes f when pressure in the inactive or idle siphons is sufficiently diminished, due to the lowering of the liquid-level in the tank A, all the chambers or wells D to D³, inclusive, but one are 95 emptied through their associated siphons F and connecting-pipes f into the traps of the siphons B to B³, with which said pipes f are connected, and the capacity of said chambers is such that the liquid therein is sufficient to 100 sufficiently fill the traps into which said liquid is discharged. The well or chamber D to D³, connected by the siphon E with the siphon which has just operated to empty the tank, is 105 emptied or partially emptied by its siphon E, so that the siphon-trap into which the siphon F, connected with said partiallyemptied chamber or well, will not be filled, as are the other traps, for the reason that said chamber is emptied below the operating-level of the siphon F therein. 110 In Fig. 7 is shown the level of the liquid in the several traps after the siphon B has operated to empty the tank. The trap of siphon B has been automatically filled by the emptying flow of water therethrough and the traps of 115 siphons B' B² B³ have been filled through their associated siphons F; but the trap of siphon B' remains but partially filled. When, therefore, the tank A is again filled, the said siphon B' so having the partially-filled trap, and therefore a weakened seal as compared with the other siphons, will next be brought into operation, while all the other siphons B to B³ will 120 remain idle. In the instance assumed the siphon B upon operating to empty the tank 125 brings into action siphon E, connected with chamber D, to empty said chamber D, so that when the time is reached that the siphons F are brought into operation in the other chambers the level of the liquid in the chamber D 130

has dropped below the operating-level of the associated siphon F, so that the trap of siphon B', with which the chamber D is connected by siphon F, is partially filled, when 5 the siphon ceases operating. It will be observed, therefore, that the next siphon to be brought into operation is the siphon B', because of the fact that its trap is not wholly filled, and its seal is therefore weaker than 10 the other siphons B B² B³. When said siphon B' is brought into operation to empty the tank, its associated chamber or well D' is emptied through the siphon E, connecting the well or chamber D' with the siphon B', so that 15 when the siphons F are brought next into operation there will be no flow of liquid from the chamber D' to fill, through the associated siphon F, the trap of the idle siphon B², with which said siphon F is connected; but the 20 traps of the other idle siphons will be filled from the wells or chambers through their associated siphons F. When the tank A is next filled, therefore, it will be emptied through the siphon B², having the partially-filled trap. 25 In this manner the rotative order of emptying the tank through the several siphons is established and maintained. In the present instance the siphons are shown as arranged in a straight line across the tank, so that in 30 order to maintain the rotative order of operating the siphons the chamber or well D³, associated with the last siphon B³ of the series, discharges through its siphon F into the trap of the first siphon B of the series. The tank- 35 emptying siphons may be arranged in a circular series and the chambers or wells suitably arranged, so as to be connected with said siphons in substantially the same manner as hereinbefore described. It will be observed 40 that upon the operation of each siphon B to B³ to empty the tank the liquid of the chamber or well D to D³, connected with that siphon through one of the siphons F, is discharged into the trap of the operating-siphon; 45 but inasmuch as the said operating-siphon fills its own trap the discharge of the liquid thereinto from the well or chamber D to D³ will not effect its operation.

It may be desirable in some instances to temporarily cut one of the tank-emptying siphons out of the operating series. This may be made desirable when the apparatus is used in connection with a sewage-purifying plant in order that the contact or filter bed upon which 55 one of the siphons discharges may be put out of action for the purpose of resting or repairing the same. I have herein shown means for so cutting out either of the siphons from the operating series, which are made as follows: 60 G designates a pipe extending transversely over the pipes e, which connect the siphons E with the several emptying-siphons B to B³, inclusive. Said pipe is closed at its ends and is connected by branch pipes with the pipes e of said siphons E. Said pipe G is provided

with cut-off valves g', located one between each two adjacent pipes e. Said valves g' remain closed so long as all of the siphons remain in the operative series. Each of the pipes e is also provided with two valves e' e², 70 located one on each side of the pipe G. The valves e' e² are normally open. The pipe e of siphon E, associated with the last chamber D³ of the series, is connected by a pipe G' with the similar pipe of siphon E, associated with the 75 chamber D. Said pipe G' is provided with a valve g². The pipe e of the siphon E, associated with the chamber D³, is also provided between the pipe G' and the chamber with a valve e³, which is normally open. With this 80 construction and arrangement, if it be assumed that the siphon B is to be next operated to empty the tank and it is desired to cut out the siphon B' in the succeeding emptying operation and to shift the emptying 85 operation to the siphon B', this may be accomplished as follows: The valve e² of the siphon E, associated with the chamber D and located between the pipe G and said chamber, is closed, the valve e associated with the chamber D' is closed, while the valve g' in the pipe G between the chambers D and D' is opened. 90 With this adjustment of the valves when the siphon B is brought into operation liquid from the chamber D' and not the chamber D is discharged into the trap of the siphon B, the connections between said chamber D' and siphon B embracing the siphon E associated with the chamber D', that part of the pipe G extending between the said siphon E, and the connecting-pipe e of the siphon E, associated with the chamber or well D, and said last-mentioned pipe e. During the operation of the siphon B liquid from the chamber D' is therefore discharged through said siphon into 95 the trap of the siphon B, so that the trap of siphon B', which communicates with the chamber D' by one of the siphons F, is not filled. When the tank A is again filled, therefore, 100 said siphon B² is next brought into action to empty the tank, because its trap is only partially filled. The valves e', e², and g' may obviously be operated to separately cut out either of the siphons from the operating series and may also be operated to cut out two or more 105 adjacent siphons of the series, if desired, and the rotative order of the newly-established series may be maintained so long as the valve adjustment be not changed.

So far as the general or broad aspect of my invention is concerned, it is to be understood that the construction of the several parts may be varied, it being only necessary that the several parts be so constructed as to perform their proper functions in connection with the 110 other parts of the apparatus.

It has been herein stated that the siphons B to B³ are constructed to operate under similar conditions, and it will be understood that this correspondence may be maintained though 115 120 125 130

the particular construction of the parts be widely varied.

Reference has been made herein to refilling the traps of certain of the siphons after each 5 operation of the siphons. It will be understood, however, that such term does not necessarily mean that the trap will be completely filled, it only being necessary that said traps be filled to a greater extent than the trap of 10 the siphon next to be brought into operation, so that the difference of liquid-levels therein will be sufficiently greater to insure the maintenance of the rotative order of operation of the siphons.

15 I claim as my invention—

1. The combination with a liquid tank or receptacle of a series of trapped siphons for emptying the same and means operating at the time of the flow of one of the siphons for 20 refilling the trap or traps of certain of the idle siphon or siphons of the series by liquid which has not passed into the operating-siphon.

2. The combination with a liquid tank or receptacle, of a series of trapped siphons for 25 emptying the same, and means operating at the time of the flow of one of the siphons for refilling from the liquid in said tank which has not passed into the operating-siphon, the trap or traps of the siphon or siphons of the 30 series with the exception of the trap of the siphon next to be brought into operation.

3. The combination with a liquid tank or receptacle, of a series of siphons for emptying the same, a plurality of chambers which are 35 severally associated with said siphons and filled from the same source supplying liquid to said tank, and means operating at the time of the flow of liquid through one of the siphons for repriming certain of the other siphons of 40 the series by liquid directed thereto from certain of said chambers.

4. The combination with a liquid tank or receptacle, of a series of siphons for emptying the same, a plurality of chambers in said tank, 45 of less depth than the tank and filled from the liquid in the tank, and means operating at the time of the flow of liquid through one of the siphons for refilling certain of the other siphons of the series by liquid directed there- 50 to from certain of said chambers.

5. The combination with a liquid tank or receptacle, of a series of siphons having trapped discharge-limbs acting severally to empty the same, a series of chambers severally associated 55 with said siphons and filled from the source supplying liquid to said tank, means whereby liquid from each chamber is discharged into and through its associated siphon when the latter is in operation, and means for discharg- 60 ing liquid from each chamber to an idle siphon of the series for the purpose of refilling the trap of the latter.

6. The combination with a liquid tank or receptacle, of a series of siphons having trapped 65 discharge-limbs for emptying the same, a se-

ries of chambers severally associated with said siphons and filled from the source supplying liquid to said tank, a siphon for emptying each of said chambers and discharging into the associated tank-emptying siphon, and 70 a second siphon communicating with each chamber and discharging into a tank-emptying siphon associated with another chamber of the series.

7. The combination with a liquid tank or receptacle, of a series of siphons having trapped discharge-limbs for emptying the same, a series of chambers severally associated with 75 said siphons and filled from the source supplying liquid to said tank, a siphon for emptying each of said chambers and discharging into the associated tank-emptying siphon, a second siphon communicating with each chamber and discharging into a tank-emptying siphon associated with another chamber of the 80 series and means for sealing the receiving ends of said chamber-emptying siphons.

8. The combination with a liquid tank or receptacle, of a series of trapped siphons for emptying the same, means for bringing said 90 siphons alternately into operation in a given order, embracing means acting during the flow of one of the siphons for filling the trap or traps of certain of the idle siphon or siphons and means for cutting certain of the siphon 95 or siphons out of the operative series.

9. The combination with a liquid tank or receptacle, of a series of siphons for emptying the same, a plurality of chambers which are 100 severally associated with said siphons and filled from the same source supplying liquid to said tank, means operating at the time of the flow of liquid through one of the siphons for sealing certain of the other siphons of the series by liquid directed thereto from certain 105 of said chambers, and means for cutting certain of the siphons out of the operative series.

10. The combination with a liquid tank or receptacle, of a series of siphons having trapped discharge-limbs for emptying the same, a series 110 of chambers severally associated with said siphons and filled from the source supplying liquid to said tank, a siphon for emptying each of said chambers and discharging into the associated tank-emptying siphon, a 115 pipe communicating with each of the siphons, valves in said pipes and the siphons, whereby either operating-siphon may be cut out of the operative series, and a second siphon communicating with each chamber and discharging 120 into a tank-emptying siphon associated with another chamber of the series.

In testimony that I claim the foregoing as my invention I affix my signature, in presence of two witnesses, this 18th day of December, 125 A. D. 1902.

SIDNEY W. MILLER.

Witnesses:

GERTRUDE BRYCE,
GEORGE R. WILKINS.
